ENGINE STARTER DRIVE

James J. Digby, Elmira, N. Y., assignor to Bendix Aviation Corporation, Elmira Heights, N. Y., a corporation of Delaware

Application March 5, 1951, Serial No. 213,943

6 Claims. (Cl. 74—7)

1

The present invention relates to an engine starter drive and more particularly to starter gearing of the type in which energization of the starting motor causes engagement of the gearing, which engagement is maintained until the engine is reliably self-operative.

It is an object of the present invention to provide a novel starter drive of the above type in which the disengagement of the gearing is dependent upon the rotational speed of the starting motor.

It is another object to provide such a device in which the means for holding the gearing engaged is positive in character and is released at a predetermined rotational speed of the starting motor, substantially irrespective of the loads on the holding means.

It is another object to provide such a device which incorporates means for yieldingly transmitting torque back from the drive pinion to the starting motor when the engine starts, while permitting the pinion to overrun, in order to assist in accelerating the motor to the releasing speed.

It is another object to provide such a device in which the drive is small and compact as related to its torque-carrying capacity and is a self-contained unit requiring no external stop for the pinion.

Further objects and advantages will be apparent from the following description taken in connection with the accompanying drawing in which:

Fig. 1 is a side elevation partly broken away and in section of a preferred embodiment of the invention showing the parts in idle position;

Fig. 2 is a similar view showing the parts in cranking position;

Fig. 3 is a view similar to Fig. 2 of a second embodiment of the invention.

In Fig. 1 of the drawing there is illustrated a power shaft 1 having a smooth reduced extension 2 providing a stop shoulder 3 against which thrust washers 4 are seated. A screw shaft 5 is fixed on the end of the power shaft 1 by suitable means such as a cross pin 6, and a control nut 7 is threaded thereon and normally retained in its idle position by means of a spring detent 8 which seats in a depression 9 of the screw shaft when in idle position.

A pinion 11 is slidably journalled on the smooth portion 2 of the power shaft for movement into and out of mesh with a gear 12 of the engine to be started, the meshing position of the pinion being defined by its engagement with the thrust washers 4.

Means for actuating the pinion from the control nut 7 is provided comprising a coupling member 13 splined to the pinion as indicated at 14, and retained thereon by a lock ring 15 seated in the extended hub 16 of the pinion and normally

2

bearing against an internal flange 17 in the coupling member. The pinion 11 is yieldingly maintained in extended relation with respect to the coupling member 13 by means of a mesh-enforcing spring 18.

The nut 7 and the coupling member 13 are provided with coaxial cylindrical surfaces 19, 21 respectively, and a clutch spring 22 is mounted on said members in position to wrap down and couple the members together frictionally when the nut 7 is rotated by the power shaft in the direction to crank the engine as indicated by the arrow a. The cylindrical surfaces 19, 21 are enlarged slightly adjacent the ends of the clutch spring 22 as indicated at 23, 24, so as to provide an initial frictional engagement between the spring and the nut and coupling member, this frictional engagement being sufficient to transmit a predetermined small amount of torque back from the pinion to the power shaft when the pinion is caused to overrun the power shaft as the engine becomes self-operative. The clutch spring 22 is maintained under endwise compression between a flange 25 on the control nut 7 and a flange 26 on the coupling member 13 by means of a barrel member 27, one end of which enters a groove 28 in the control nut as indicated at 29, and which has a flange 31 at its other end embracing the coupling member 13.

The screw shaft 5 is provided with an enlarged head 32, and a radial pin 33 is fixedly mounted therein in any suitable manner and serves as a pivot for a movable abutment member 34 which accordingly swings tangentially to the drive. The surface of the head 32 of the screw shaft is provided with ratchet teeth 35 which cooperate with similar teeth 36 on the abutment member 34, the teeth being arranged to permit the latter to swing into operative position as shown in Fig. 2, but to positively prevent the same from returning to idle position while the teeth are engaged. The operating position of the abutment member is defined by a stop pin 37 so located that when said member engages the pin the axis of the abutment member is nearly but not quite parallel to the axis of the drive. The angle between the axis of the abutment member and axis of the drive when in operative position is preferably in the neighborhood of 5 or 10 degrees.

Means for urging the abutment member toward its operating position and for yieldingly holding the ratchet teeth 35, 36 in engagement is provided in the form of a torsion and compression spring 38 anchored at one end of the pivot pin 33 and its other end to the abutment member as indicated at 39 (Fig. 2).

When the abutment member is in operating position as shown in Fig. 2, it provides a positive abutment which arrests demeshing movement of the control nut 7 at the position indicated by the

dotted line 41 in Fig. 2, thus maintaining the pinion 11 in mesh with the engine gear 12.

In operation, starting with the parts in the positions illustrated in Fig. 1, rotation of the power shaft 1 by the starting motor not illustrated causes the control nut 7 to move to the right, traversing the pinion 11 into mesh with the engine gear 12 until its movement is arrested by the thrust washers 4. If the meshing movement is interrupted by abutment of the pinion teeth 18 against the teeth of the engine gear, the spring 18 is compressed until sufficient torque is built up to index the pinion into proper registry with the tooth spaces of the engine gear, whereupon the meshing movement is completed.

When the longitudinal movement of the pinion is arrested by the thrust washers, torque is transmitted from the control nut through the clutch spring 22 which wraps down and grips the surfaces 19, 21 so as to couple the nut 7 to the coupling member 13 and pinion 11 to crank the engine.

During the meshing movement of the control nut, the abutment member 34 is permitted to rotate under the impulse of the spring 38 until it occupies the position shown in Fig. 2, where it is positively held by the engagement of the ratchet teeth 35, 36. When the engine fires, acceleration of the pinion by the engine gear causes it to overrun the power shaft, and the nut 7 is threaded back along the screw shaft 5 by the torque transmitted through the clutch spring 22 by its frictional engagement with the enlarged portions 23, 24 of the control nut and coupling member. This movement, however, is arrested by the abutment member 34 until the engine has become reliably self-operative. When this occurs, the starting motor will have accelerated sufficiently to cause centrifugal force to move the abutment member 34 radially outward against the compression of the spring 38 so as to disengage the ratchet teeth 35, 36, and then to rotate the abutment member against the torsional force of the spring back to idle position, whereupon the control nut and its associated parts are permitted to return to their idle position where they are retained by the anti-drift detent 8.

Should the operator deenergize the starting motor before it has attained sufficient speed to cause release of the abutment member 34, if the engine remains self-operative, torque is transmitted back from the pinion 11 through the clutch spring 22 to gradually accelerate the power shaft and motor up to the releasing speed, whereupon the pinion 11 is demeshed in the usual manner.

In Fig. 3 of the drawing there is illustrated a second embodiment of the invention which is self-contained, in that no external stop for the pinion is required. As there shown, the threads of the screw shaft 5A terminate adjacent the free end of the screw shaft, forming abutments 42 which arrest the meshing movement of the control nut 7 thereon. The anchored end of the screw shaft 5A has a smooth reduced portion 43 on which a ring 44 is fixedly mounted in any suitable manner and performs the function of the driving head 32 in the first embodiment of the invention.

The remaining parts of this embodiment are the same as in the first embodiment and are similarly numbered, and the operation of the drive is the same except that the meshing position of the pinion is in this case defined by the abutments 42 on the screw shaft instead of by the thrust washers 4.

Although but two embodiments of the invention have been shown and described in detail, it will be understood that other embodiments are possible and that changes may be made in the precise form and arrangement of the parts without departing from the spirit of the invention.

I claim:

1. In an engine starter drive a power shaft, a screw shaft fixed thereon, a control nut threaded on the screw shaft, a pinion slidably journaled on the power shaft for movement into and out of mesh with a gear of the engine to be started; means connecting the control nut to the pinion including an overrunning clutch, a radial pin fixed to the screw shaft, an abutment member pivoted thereon for movement into and out of position for blocking the demeshing movement of the pinion; and centrifugally releasable means for holding the abutment member in blocking position.

2. An engine starter drive as set forth in claim 1 in which the overrunning clutch incorporates a friction coupling yieldably transmitting torque from the pinion to the control nut when the pinion overruns the power shaft.

3. An engine starter drive as set forth in claim 1 in which the means for holding the abutment member in blocking position comprises a ratchet connection between the abutment member and the screw shaft, and including further a spring on the pivot pin urging the abutment member into blocking position, and the ratchet connection into engagement.

4. An engine starter drive as set forth in claim 3 including further means for arresting the swinging movement of the abutment member into blocking position before the abutment member becomes aligned with the axis of the power shaft.

5. In an engine starter drive, a power shaft, a pinion slidably journaled thereon for movement into and out of mesh with an engine gear, means responsive to acceleration of the power shaft for moving the pinion into meshing position, an abutment member, means for pivotally mounting the abutment member on the power shaft for movement into and out of position for blocking the demeshing movement of the pinion; yielding means for moving the abutment member into blocking position, and means for positively holding the abutment member in blocking position; said abutment member being movable by centrifugal force to release the holding means and return the abutment member to idle position at a predetermined rotational speed of the power shaft.

6. An anti-kickout engine starter drive including a pinion, means for moving the pinion into and out of mesh with an engine gear and for rotating the pinion; means including an abutment member pivotally mounted on the moving means, yielding means urging the abutment member into operative position for blocking demeshing movement of the pinion; and centrifugally-released means for positively holding the abutment member in operative position.

JAMES J. DIGBY.
